(57) **CLAIM**

The ornamental design for a hand caster, as shown and described.

DESCRIPTION

FIG. 1 is a front perspective view showing my design;

FIG. 2 is a rear perspective view thereof;

FIG. 3 is a top view of a removable screw cap thereof;

FIG. 4 is a bottom view thereof; and,

FIG. 5 is a frontal elevational view thereof.

The intended uses are for a hand line fishing system that is easily casted to catch fish and storage means for hooks, sinkers, floats, etc...
